(57) **CLAIM**

The ornamental design of a vitrectomy probe as shown and described.

DESCRIPTION

FIG. 1 is an isometric view of the vitrectomy probe of the present invention.

FIG. 2 is a front view of the vitrectomy probe of the present invention.

FIG. 3 is a rear view of the vitrectomy probe of the present invention.

FIG. 4 is a top view of the vitrectomy probe of the present invention.

FIG. 5 is a bottom view of the vitrectomy probe of the present invention.

FIG. 6 is a first side view of the vitrectomy probe of the present invention; and,

FIG. 7 is a second, opposing side view of the vitrectomy probe of the present invention.

The broken lines in the drawings indicate portions of the vitrectomy probe that form no part of the claimed design.

1 Claim, 4 Drawing Sheets
